ORE SEPARATOR OF ALTERNATE-CURRENT ELECTROMAGNET.

Application filed March 19, 1925. Serial No. 16,604.

This invention relates to a machine for selecting and separating useful minerals from powdered ores by means of a rotating, or shifting, magnetic field caused by polyphase 5 alternate electric current, and the object thereof is to avoid the disadvantages of separators of this kind hitherto in use and to obtain high grade concentrates by means of a comparatively simple machine.

10 My invention consists in this that powdered ore is charged in a hopper, and by the action of a rotating, or shifting (shifting in a straight line), magnetic field produced by polyphase alternating electric current, the 15 particles of the mineral are given revolving motion, and are attracted by the iron core which has the greatest attraction, thus separating high grade concentrates from tailings. According to my invention, there is 20 no necessity of mechanically revolving the machine, as in the case of machines hitherto in use, and in magnetic separators in which direct current electricity is used, there is a 25 drawback of tailings being attracted together with mineral particles, while according to my invention, the magnetic field, by imparting rotation to every particle of mineral, causes such particles to be thoroughly separated from the tailings. Thus not only 30 high grade concentrates can easily be obtained but there is no necessity of demagnetizing them as before. Moreover, the invention possesses the additional advantage of rendering unnecessary the provision of a direct current generator for obtaining direct 35 current electricity.

The accompanying figures show a few examples for carrying my invention into practice, of which—

40 Fig. 1 is a vertical front section of an alternating current magnetic ore separator of wet system, and

Fig. 2 a plan thereof, half in section.

45 Fig. 3 is a vertical front section of a modified form of my invention for obtaining more refined concentrates by repeating the process of separating mineral from tailings.

50 Fig. 4 is a vertical front section of another modification of my invention, in which a rotary magnetic field is provided within a water vessel.

Fig. 5 is a section of yet another modification in which a flat magnetic field is used

instead of a round one and an angular water vessel instead of a cylindrical one, and

Fig. 6 is a side section thereof.

In the figures, (1) is a wooden water vessel (this vessel may preferably be made with insulating substance such as pottery) divided into three parts, the uppermost of which is a hopper (2), the next is an ore separating chamber (3), and the lowest is again divided into three, of which (4) is a tailings chamber, (5) a middlings chamber, and (6) a concentrates chamber. Between the hopper (2) and separating chamber (3), there are a fixed bottom (7) and a movable bottom (8), and an opening (9) between these bottoms is adjusted by a screw (10) by moving the movable bottom (8). Above the separating chamber (3), there is a water pipe (11) along the side wall perforated with numerous small holes, which project water in the direction as shown in Fig. 1. Just below this water pipe 11, the separating chamber is provided with an annular inclined shelf 12, and below said shelf with a plurality of annular inclined baffles or deflectors 14 superposed one above another, the baffles being spaced from the wall of the separating chamber so as to form an annular channel 13 between the upper edges of the baffles and the wall of the chamber. As shown in the drawings the baffles are inclined downwardly toward the center of the chamber, at such an angle that impurities contained in the ore will slide by gravity on the baffles toward the center of the chamber. It will be noted that the baffles are successively narrower toward the lower end of the separating chamber. By reason of this construction, the impurities that fall down from one baffle do not fall upon the next lower one, but will be directed away therefrom.

In the inner circumference of the baffles 95 a large number of thin plate pieces (15) are inserted at a suitable angle with the radius. In order to fill up the central space of the separating chambers (3) a cylinder (16) is inserted, and around the separating chamber 100 (3), there is provided a field magnet (17) to produce a rotary magnetic field, the construction of which magnet is the same as the stator of a polyphase induction motor, that is, it consists of an iron core of numerous 105 thin plates piled one upon another, and the

- inner circumference of this iron core is cut into numerous grooves in which a coil is regularly wound. These are enclosed within an outer casing (20) and a cover (21), and are supported upon supports (22).
- According to my invention ore is dressed as follows:—
- Powdered ore mixed with a suitable amount of water is fed into the hopper (2). Then it passes by its own weight into the separating chamber (3) through the opening (9), and by the action of the water spouting from the pipe (11), the ore flows toward the center over the shelf (12), the ore and water being given a rotary motion by the thin pieces (15) which act something like vanes of a water wheel, and falling down around and along the surface of the cylinder (16). At the same time, the particles of pure mineral in the ore, being acted upon by the rotating magnetic field caused by the polyphase electricity which flows through the coil, rotate one by one, thus being well separated from tailings, and attracted to the wall of the water vessel, the tailings having no property to be attracted by magnetism, but having the tendency to collect toward the centre, will fall down from the baffles.
- In other words, the concentrates before reaching the wall strike against the thin pieces (15) and are separated from the tailings, which slide down the baffles by their own weight and fall down therefrom, while the concentrates, being attracted by the magnetism, roll upward against the inclination of the baffles in the direction opposite to that of the rotating magnetic field. This rotating motion imparts to the water revolving motion and thus assists the separation of concentrates from tailings, thus the concentrates which reach the wall of the water vessel are very pure, and fall down revolving along the channel (13) by their own weight and enter into the concentrate chamber (6), the next purest into the middlings chamber (5), while the impurities and those falling from the inner edges of the baffles fall into the tailings chamber (4). The whole are discharged through passages (23), (24) and (25) outside of the water vessel.
- In the modification shown in Fig. 3, the ore is repeatedly separated and purer concentrates are obtained. For this purpose, a water pipe (26) and a water shelf (27), similar in construction to (11) and (12) described before, are fitted at the middle part of the separating chamber, and also a shelf (28) to lead tailings falling from the upper separating chamber to the lower separating chamber. Then the concentrates which fall down on the water shelf (27) are made to rotate inwardly by the water spouting from the water pipe (26), and are fur-
- ther separated in the lower separating chamber.
- In this invention it is not necessary to provide an iron core to produce a rotating magnetic field outside of the water vessel, but as shown in Fig. 4, a separating chamber (3) may be provided around an electromagnet (17) of a construction like a wound coil rotor of an induction motor.
- Also, in this invention the use of a circular iron core which produces a rotating magnetic field is not necessary, but as shown in Figs. 5 and 6 a flat field magnet (17) may be used, and a shifting magnetic field caused thereby may be utilized to fulfill the same object.
- The above description refers to a wet system in which water is used, but it goes without saying that this invention can be used with a dry system.
- Claims:—
1. An ore separator, comprising in combination, a separating chamber provided interiorly thereof with a plurality of annular inclined baffles spaced from the wall of said chamber thereby to form an annular channel between said wall and the upper edges of the baffles, a receiving chamber below said separating chamber and in communication with said channel, and electrical means disposed contiguous to the wall of said chamber for producing a rotating magnetic field thereby to impart rotary motion to mineral particles and cause them to travel upward on the baffles and fall into said channel. 95
  2. An ore separator, comprising in combination, a separating chamber provided interiorly thereof with a plurality of annular inclined baffles spaced from the wall of said chamber thereby to form an annular channel between said wall and the upper edges of the baffles, a receiving chamber below said separating chamber and in communication with said channel, and a polyphase alternating-current electromagnet disposed contiguous to the wall of said chamber for producing a rotating magnetic field thereby to impart rotary motion to mineral particles and cause them to travel upward on the baffles and fall into said channel. 105
  3. An ore separator, comprising in combination, a separating chamber provided interiorly thereof with a plurality of annular inclined baffles spaced from the wall of said chamber thereby to form an annular channel between said wall and the upper edges of the baffles, said baffles being superposed relatively to each other and each succeeding baffle toward the lower end of the chamber being narrower than the preceding one, a receiving chamber below said separating chamber and in communication with said channel, and electrical means disposed contiguous to the wall of said chamber for 110
  - 120
  - 125
  - 130

producing a rotating magnetic field thereby to impart rotary motion to mineral particles and cause them to travel upward on the baffles and fall into said channel.

- 5 4. An ore separator, comprising in combination, a separating chamber provided interiorly thereof with a plurality of annular inclined baffles spaced from the wall of said chamber thereby to form an annular channel between said wall and the upper edges of the baffles, a plurality of plates secured in the inner peripheries of said baffles, said plates being inclined in a direction opposite to that of the baffles, a receiving chamber 10 below said separating chamber and in communication with said channel, and electrical means disposed contiguous to the wall of said chamber for producing a rotating magnetic field thereby to impart rotary motion to mineral particles and cause them to travel upward on the baffles and fall into said channel.
- 15 5. An ore separator, comprising in combination, a separating chamber provided interiorly thereof with a plurality of annular inclined baffles spaced from the wall of said chamber thereby to form an annular channel between said wall and the upper edges of the baffles, a hopper above and in communication with said separating chamber, adjustable means for limiting the communication between the hopper and said chamber, a receiving chamber below said separating chamber and in communication with said channel, and electrical means disposed contiguous to the wall of said chamber for producing a rotating magnetic field thereby to impart rotary motion to mineral particles and cause them to travel upward on the baffles and fall into said channel.
- 20 6. An ore separator, comprising in combination, a separating chamber provided adjacent to its upper end with an inclined annular shelf, a hopper disposed above said chamber and adapted to deliver ore on to said shelf, means for directing said ore toward the lower edge of the shelf, a plurality of superposed, inclined, annular baffles disposed below said shelf in spaced relation to the wall of the chamber thereby to provide an annular channel between said 25 wall and the upper edges of said baffles, each succeeding baffle toward the lower end of the chamber being narrower than the preceding one, a plurality of plates secured in the inner peripheries of said baffles, said plates being inclined in a direction opposite to that of the baffles, a polyphase alternating-current electromagnet disposed in contiguous relation to the wall of said chamber for producing a rotating magnetic field thereby to impart rotary motion to mineral particles and cause them to travel upward on the baffles and fall into said channel, a receiving chamber below said separating chamber and in communication with said 30 channel for receiving said mineral particles, a middlings receiving chamber below said separating chamber, and a tailings receiving chamber also disposed below said separating chamber, said tailings and middlings receiving chambers being closed to said channel but communicating with the central opening between the baffles.
- 35 7. An ore separator, comprising in combination, a separating chamber provided adjacent to its upper end with an inclined annular shelf, a hopper disposed above said chamber and adapted to deliver ore on to said shelf, a water supply pipe disposed adjacent to the wall of said chamber above said shelf and provided with a plurality of perforations adapted to direct jets of water toward the lower edge of the shelf, a plurality of superposed, inclined, annular

baffles disposed within said chamber in spaced relation to the wall thereof thereby to provide an annular channel between said wall and the upper edges of said baffles, 55 a receiving chamber below said separating chamber and in communication with said channel, and a polyphase alternating-current electromagnet disposed in contiguous relation to the wall of said chamber for producing a rotating magnetic field thereby to impart rotary motion to mineral particles and cause them to travel upward on the baffles and fall into said channel.

8. An ore separator, comprising in combination, a separating chamber provided adjacent to its upper end with an inclined annular shelf, a hopper disposed above said chamber and adapted to deliver ore on to said shelf, means for directing said ore toward the lower edge of the shelf, a plurality of superposed, inclined, annular baffles disposed below said shelf in spaced relation to the wall of the chamber thereby to provide an annular channel between said 75 wall and the upper edges of said baffles, each succeeding baffle toward the lower end of the chamber being narrower than the preceding one, a plurality of plates secured in the inner peripheries of said baffles, said 80 plates being inclined in a direction opposite to that of the baffles, a polyphase alternating-current electromagnet disposed in contiguous relation to the wall of said chamber for producing a rotating magnetic field thereby to impart rotary motion to mineral particles and cause them to travel upward on the baffles and fall into said channel, a receiving chamber below said separating chamber and in communication with said 85 channel for receiving said mineral particles, a middlings receiving chamber below said separating chamber, and a tailings receiving chamber also disposed below said separating chamber, said tailings and middlings 90 receiving chambers being closed to said channel but communicating with the central opening between the baffles.

In testimony whereof I have signed my name to this specification.

MITSUO KOIZUMI.
